UNITED STATES PATENT OFFICE.

PAUL CARL EDUARD GOETZE, OF HAMBURG, GERMANY, ASSIGNOR OF ONE-HALF TO FIRM OF FRANZ SANDER, OF HAMBURG, GERMANY.

METHOD OF TESTING LUBRICANTS.

SPECIFICATION forming part of Letters Patent No. 700,683, dated May 20, 1902.

Original application filed July 25, 1901, Serial No. 69,724. Divided and this application filed October 21, 1901. Serial No. 79,450. (No model.)

To all whom it may concern:

Be it known that I, PAUL CARL EDUARD GOETZE, a subject of the German Emperor, and a resident of Hamburg, in the German Empire, have invented a certain new and useful Improved Method of Testing Lubricants, (being a division of application, Serial No. 69,724, filed July 25, 1901,) of which the following is a specification.

10 This invention relates to an improved method of testing lubricants and ascertaining the quantity, quality, and efficacy of lubricants used in connection with the working or pressure medium in the cylinders of piston-15 engines, particularly steam-driven engines.

The chief object of the invention is to supply means which will enable in each individual case of making visible signs by which the condition and relative amounts of the 20 lubricant existing in the working medium at each portion of the stroke of the piston may be observed and of ascertaining by such registering the most suitable lubricant for any particular engine, whether the distribution 25 of the lubricant in the interior of the steam-cylinder is uniformly carried out, and whether the cylinder receives too much or not enough lubricant—in other words, how far the lubricant may be economized. Hitherto 30 in order to ascertain these facts so important for the undisturbed working of piston-engines it was necessary to stop the engine and remove the cylinder-cover. Besides the objectionable interruption in the service, the 35 aforementioned procedure has the further disadvantage that by inspection of the machine while it is at a standstill it is only possible to ascertain the faulty lubrication, but not the cause of it.

40 My invention consists, mainly, in that during the working of the machine steam or other working medium from the cylinder is caused to impinge on a surface, (preferably on a paper strip,) which is preferably moved to correspond with the piston motion. The lubricant mixed with the steam is deposited on the surface, and thus the intensity, distribution, and coloring of the grease or oil spot

enables an estimate to be formed as to the quantity, quality, and distribution of the lubricant. 50

The drawing indicates a form of apparatus suitable for carrying out the method and consists of a short tube *a*, fitted at its free end with a tap *c*, formed with a nozzle *b*, and at 55 its opposite end with a suitable screw joint or union *d*, preferably in the form of a cock, designed to be secured to the indicator-socket of an engine-cylinder.

The tube *a* is provided intermediate its 60 ends with a pressure-gage *e* and thermometer *f*, and the box of the tap with a bent arm *g*, suitably connected thereto. The said bent arm carries at its free end an indicator-drum *h*, such as is customarily employed in steam-65 indicators and so disposed as to face with its peripheral surface the nozzle *b* of the tap *c*. The drum *h* is adapted to be rotated or oscillated on its axis by the cord *i* in the manner usually adopted for indicators in opposition to a spring arranged in the interior of the drum and not shown in the drawing. The drum is further provided with tongues or clips *k* for fastening the paper strip or card that is to receive the record on the drum. 75

The operation is as follows: The card having been secured to the cylinder *h* and the union *d* secured to the cylinder of the engine and the cord *i* secured to a moving part of the engine or a suitable reducing motion, 80 so that said cylinder *h* will be moved either in synchronism with or proportionately to the motion of the piston of the engine, the tap *c* is opened to allow a jet of steam from the nozzle *b* to impinge upon the card carried by 85 the cylinder *h*. The oil in the steam will leave a record on the card after the moisture of the steam has evaporated. It is clear that in this manner a correct estimation of the distribution of the lubricant is obtained, 90 while at the same time proof is furnished whether the steam affects the lubricant favorably or decomposes the same, and, further, also, whether the distribution is uniform or interrupted for a portion of the path, so as 95 to lead to the wearing of the piston at such

parts. The defects thus ascertained may then be overcome by the use of other lubricants or by a change in the supply, &c. By further experiments or records it may then 5 be stated whether by these changes of the lubricant or in its supply the desired result has been obtained or not.

Having fully described my invention, what I claim, and desire to secure by Letters Patent, is—

1. The herein-described method, which consists in causing a jet of fluid from the power-cylinder of a motive-fluid-operated engine to impinge upon a surface moving across said 15 jet and capable of indicating the relative quantity of lubricant mixed with the steam of said jet, substantially as and for the purpose set forth.

2. The herein-described method, which consists in causing a jet of fluid from the power-cylinder of a motive-fluid-operated engine to impinge upon a surface moving across said jet in synchronism with the movements of 20 the engine-piston and capable of indicating

the relative quantity of lubricant in said jet, 25 substantially as and for the purpose set forth.

3. The herein-described method, which consists in causing a jet of fluid from the power-cylinder of a fluid-operated engine to impinge upon a surface capable of visibly indicating 30 and recording the lubricant therein and moving across said jet, and simultaneously indicating the pressure under which the jet is produced, substantially as and for the purposes set forth.

4. The herein-described method, which consists in causing a jet of fluid from the power-cylinder of a motive-fluid-operated engine to impinge upon a surface oscillating in front of the jet in synchronism with the reciprocations of the engine-piston, said surface capable of visibly indicating and recording the lubricant forced thereon, substantially as and for the purposes set forth.

PAUL CARL EDUARD GOETZE.
